FISH LURE

Earl B. Ludwick, Downey, Calif., assignor to Nebco Precision Manufacturing Co., Bellflower, Calif., a partnership

Application August 5, 1957, Serial No. 47,236

Term of patent 14 years

(Cl. D31—4)

FIG. 1.

FIG. 2.

Fig. 1 is a front perspective view of a fish lure, or similar article, embodying my new design; and

Fig. 2 is a top plan view thereof, the hook shown at the right end of Figs. 1 and 2 being shown in slightly different positions in these figures.

The dominant features of the design are shown by solid lines in the drawing and the rear of the design is substantially like the front thereof.

I claim:

The ornamental design for a fish lure, or similar article, substantially as shown and described.
